DESIGN FOR A TRAVELING BAG

Dexter G. White, Philadelphia, Pa.

Application May 19, 1938, Serial No. 77,273

Term of patent 7 years

To all whom it may concern:

Be it known that I, Dexter G. White, a citizen of the United States, residing in Philadelphia, county of Philadelphia, State of Pennsylvania, have invented a new, original, and ornamental Design for Traveling Bags, of which the following is a specification, reference being had to the accompanying drawing, which forms a part thereof.

Fig. 1 is a perspective view of a traveling bag embodying my design, the bag being closed.

Fig. 2 is a perspective view of the bag in open position.

I claim:

The ornamental design for a traveling bag, as shown and described.

DEXTER G. WHITE.
